UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

SEWING-MACHINE.

1,080,343.

Specification of Letters Patent.

Patented Dec. 2, 1913.

Application filed April 1, 1911. Serial No. 618,348.

To all whom it may concern:

Be it known that I, GEORGE S. HILL, a citizen of the United States, residing at Strafford, in the county of Strafford and State 5 of New Hampshire, have invented certain Improvements in Sewing-Machines, of which the following description, in connection with the accompanying drawings, is a specification, like reference characters on the drawings indicating like parts in the several figures.

The invention relates to new and useful improvements in sewing machines, and more especially to the mechanism for vibrating 15 a needle laterally relative to its line of reciprocation.

An object of the invention is to provide a needle-vibrating mechanism wherein the vibrating parts are light and few in number, 20 and wherein the movements imparted to the needle are positive in character, so as to avoid lost motion and excessive wear of the parts.

A further object of the invention is to provide 25 a needle-vibrating mechanism wherein the needle bar is reciprocated in a fixed line and the needle is vibrated laterally relative to the line of reciprocation of the needle.

A further object of the invention is to provide 30 means whereby a needle carrier is vibrated relative to a needle bar, and the carrier moved longitudinally of the needle bar during its vibrations.

These and other objects will in part be 35 obvious, and will in part be hereinafter more fully described.

In the drawings which show by way of illustration one embodiment of the invention,—Figure 1 is a vertical sectional view 40 substantially on the line of feed, showing a sewing machine with my improvements applied thereto; Fig. 2 is a detail perspective view showing the manner of operating the feed dog from the bender lever; also 45 showing the presser foot mechanism and the relative position of the looper; Fig. 3 is a detail perspective view showing the needle-vibrating mechanism, take up and the looper-operating mechanism; Fig. 4 is a horizontal 50 sectional view through the casing for the bender lever, showing the work support in plan and with parts broken away and removed to show the operating mechanism beneath the same; Fig. 5 is a detail perspective 55 view of the thrum gatherer with parts

broken away to show the manner of attaching the same to the work support; Fig. 6 is a detail view partly in section, showing the manner of bending the material into the path of the needle; and Fig. 7 is a detail 60 showing the manner of covering the thrum ends and stay cords by my improved stitching mechanism.

In carrying out the invention, the stitch-forming mechanism consists of a needle 65 which is so mounted on a needle bar that the needle may be vibrated laterally and reciprocated back and forth in a plane substantially parallel to the work support, so that the needle may be caused to enter the material at one point and emerge therefrom on the same side of the material, so as to make a blind stitch, and then be vibrated laterally and again caused to enter and emerge from the material to make a second blind 75 stitch and form cross connecting threads between the blind stitches, which may be used to cover thrum ends in finishing a button-hole strip, or which may be used for other purposes. The needle is reciprocated from 80 a driving shaft beneath the work support, and is also vibrated laterally by a worm gear connection from the driving shaft. The material is bent into the path of the needle by the bender, and the stitches are locked 85 by the usual form of looper, which, as herein shown, is preferably of the shuttle type. The material is fed so as to space the stitches by a feeding mechanism located beneath the 90 work support.

Referring more in detail to the drawings, the sewing machine as herein illustrated consists of a hollow casing having a supporting base 1 and a work support 2, which is hinged to the base at 3, so that the work support may be raised and lowered to give access to the operating parts beneath the same. Mounted beneath the work support is a needle 4, which is clamped in a needle carrier 5, which in turn is mounted on a needle bar 6. The needle bar 6 reciprocates in a bracket 7, which freely engages the needle bar adjacent the carrier 5 and a bracket 8, which engages the outer end of the needle bar. These 100 brackets are preferably secured to the under face of the work support 2, so that when the work support is raised the needle bar will be moved therewith.

The needle bar is reciprocated in the supporting brackets 7 and 8 by a link 9 which 110

is connected to a collar 10 at one end and to a crank 11 at the other end, which crank is carried on the forward end of a driving shaft 12. The driving shaft 12 is also mounted in supporting brackets carried on the under face of the work support and may be driven in any desired way. The needle bar is preferably constructed so as to reciprocate in its bearings without turning thereby. The needle carrier 5 is interiorly threaded and engages a corresponding thread 13 indicated in dotted lines in Figs. 1 and 3. The needle carrier 5 is swung about the axis of the needle bar, so as to vibrate the needle laterally and position the same for forming laterally spaced stitches. As herein shown the needle carrier turns relative to the needle bar on the threaded connection 13.

As a means for vibrating the needle carrier laterally, a bar 14 is rigidly connected to the carrier at one end, and at its other end is connected rigidly to an arm 15, which is connected to a collar 16, which in turn is loosely mounted on the needle bar. A link 17 extends through a slotted bearing 18 in a bracket on the under side of the work support, and is free to slide longitudinally in said slotted bearing. Said link 17 is formed with a collar 19, which freely engages the bar 14, so that the bar 14 may slide longitudinally in said collar. The other end of the link 17 is connected to an eccentric member 20, carried by the outer end of a shaft 21, mounted in any desired way underneath the work support. The shaft 21 carries a worm gear 22, which is arranged with its axis at right angles to the axis of the driving shaft 12. A worm gear 23 is mounted on the driving shaft 12, and meshes with the worm gear 22. These gears 22 and 23 are so proportioned that two revolutions of the gear 23 are required to give one revolution of the gear 22. As the driving shaft 12 rotates, the link 17 will be moved longitudinally, and through its connection with the bar 14 will vibrate the carrier 5 on the needle bar 6, through its threaded connection therewith, and will also vibrate the arm 15 on the needle bar 6 through the loose collar connection 16. This threaded connection between the carrier 5 and the needle bar 6 is preferably for the purpose of assembling the parts and eliminating all lost motion between the carrier and the needle bar. I may, therefore, form said threaded connection either as a right hand thread or a left hand thread, and I prefer to form a very fine thread, so that the longitudinal movement of the carrier on the needle bar is comparatively slight.

It will be readily seen that the carrier may be quickly turned on the end of the bar through its threaded connection and in its various angular positions relative to the

needle bar will be firmly held against any longitudinal movement on the bar, except when the carrier is turned relative to the needle bar.

Cooperating with the needle is a looper 24, which is mounted to oscillate about the axis of a shaft 25. The shaft 25 at its lower end carries a crank arm 26, which co-operates with a forked lever 27, which in turn is vibrated by a link 28 connected with a crank pin on the forward end of the driving shaft 12. This looper is preferably of the shuttle type, and oscillates about a fixed center. It will readily be seen that when a left hand thread is formed between the needle bar 80 and the carrier 5 and when the carrier 5 is oscillated, the point of the needle will be moved toward and from the path of movement of the beak of the looper. Therefore, this threaded connection between the needle carrier and the needle bar would have a slight tendency to compensate for the different relative positions of the needle eye and the beak of the shuttle, when the needle is in its two lateral positions. This movement of the needle relative to the path of movement of the beak of the looper is, however, unnecessary where the range of lateral vibration of the needle is slight, as in the present machine, and the main purpose, 95 therefore, of this threaded connection between the needle carrier and the needle bar is to take up all lost motion. If the thread forming the connection between these parts is sufficiently fine, the needle carrier may in fact be moved in a direction so as to tend to throw the needle and the looper out of proper co-operation, and in the present machine the actual co-operation between the needle and looper will not be disturbed. It 100 will, therefore, be understood that the thread connecting the needle carrier and needle bar may be either a right hand or a left hand thread, and that the essential feature is to provide an easy manner of assembling these parts, and to avoid all possible chance for lost motion in this connection.

As a means for feeding the material, I have provided a feed dog 29 which is carried by a feed bar 30, pivoted to a feed rocker 31. The feed rocker is moved back and forth through a connection with an eccentric on the driving shaft 12, as shown in dotted lines in Fig. 4.

As a means for bending the material into the path of the needle, I have provided the work support with a throat plate having a groove 32 therein, and a bender 33 operates to bend the material into the groove and into the path of the needle. This bender is carried by a lever 34, which is pivoted to a casing carried by the work support, and extends beneath the work support where the same is operated by an eccentric 35.

As a means for raising and lowering the feed dog, so that the same will be raised when the bender is raised, and lowered when the bender is lowered, I have formed 5 the bender lever with an arm 36, which projects laterally along the side of the feed bar 30, and carries a pin 37, which works in a slot 38 in the feed bar. This allows the feed bar to be moved longitudinally, and as 10 the bender lever is moved up and down the feed dog will also be moved up and down therewith. Coöoperating with the feed dog is a presser foot 39, carried by a lever pivoted at 40, and which presser foot is raised 15 and lowered through a rod 41, extending beneath the work support.

The needle thread is led through a tension 42. As a means for releasing the tension when the presser foot is raised, I have 20 formed the presser lever with a releasing finger 43, which has its outer end located adjacent the tension 42, and when the lever is raised, said finger will be forced between the tension disk to release all tension on the 25 thread, so that the material may be readily removed from the machine. The thread from the tension passes through a take up 44, which may be operated in any desired way from the driving shaft 12.

30 My machine is especially adapted for finishing buttonhole strips, such as shown in Fig. 7. The thrum ends and stay cord running from one buttonhole to another are covered by presenting the material to the 35 needle so that a stitch is formed first on one side of the thrum ends and then on the other, and the cross threads running from one stitch to another will cover said thrum ends.

40 In order to gather in the thrum ends and stay cord so that the needle will with certainty enter the material entirely at one side thereof, and then entirely at the other side thereof, I have provided a thrum gatherer 45, (see Figs. 1 and 5). This thrum gatherer 45 is formed with upwardly bent ends 46, which are spaced so as to form a delivering notch 47. The upwardly bent ends 46 are so disposed as to gather in the thrums 50 which pass out through the notch 47. This thrum gatherer 45 is secured to a disk 48 by suitable screws, and the disk 48 is mounted so as to turn on the work support, so that the thrum gathered may be swung from a 55 position directly in front of the needle, or in line with the feed to one side, or in a position at an angle to, the line of feed. The looper is located directly in front of the needle, and is, therefore, positioned directly 60 underneath the thrum gatherer. I have cut away the work support at 49, (see Fig. 2), directly above the looper, and the thrum gatherer when in normal position covers said opening 49. When it is desired to obtain 65 access to the looper for re-threading,

the thrum gatherer may be quickly turned to one side, which will expose the looper. After the looper has been replaced, the thrum gatherer may be moved to normal position, and thus cover the looper. It will, 70 therefore, be seen that by this construction, the thrum gatherer serves not only the purpose of covering the thrums and positioning the same for the stitching mechanism, but also has the covered plate for the opening 75 in the work support which exposes the looper.

As a means for holding the thrum gatherer in normal position, I have provided a ball 50, which is located in a socket 80 in the support underneath the disk 48 carrying the thrum gatherer, and is spring pressed outwardly toward said disk. This ball is adapted to engage a depression in the under face of the disk on which the thrum gatherer is supported, and will hold the 85 same in normal position.

As a means for giving ready access to the needle for threading, and also to the take up, I have formed the work support with a 90 slot 51, which extends over the needle bar and its operating mechanism. Said slot is preferably covered by a cover plate, indicated as broken away in dotted lines at 52. The bracket 7 which supports the forward 95 end of the needle bar, is preferably a V-shaped bracket, and spans the slot 51 in the work support, which gives a proper space for the movement of the carrier and the parts for vibrating the same. The 100 bracket 8 is attached at one side of the slot 51, and projects downwardly and laterally, so as to properly support the outer end of the needle bar.

The thrums which are to be covered by 105 the stitch-forming mechanism are on the under side of the material, and in order to aid the operator in properly guiding the material to direct the thrums to the thrum gatherer and the stitch-forming mechanism, 110 I have provided a guide 53, which is preferably secured to the presser foot and projects forwardly thereof. The forward end of the guide is so positioned relative to the stitching point that if the ends of the buttonhole are led directly underneath the same, then the thrums will be properly gathered and covered by the stitches.

It is obvious that minor changes in the details of construction may be made, or the 120 arrangement of parts may be varied, without in any way departing from the spirit of my invention, as set forth in the appended claims.

While I have designed my machine with a 125 special view that the same shall be used for finishing buttonhole strips, it is obvious that the stitch-forming mechanism herein shown and claimed may be used in other types of machines, and for other purposes.

Having thus particularly described my invention, what I claim as new and desire to secure by Letters Patent, is:—

1. A sewing machine including in combination, a work support, a needle bar located and operating at one side of said work support and in substantially the same path, a needle carried thereby, a driving shaft located beneath the work support, means for reciprocating the needle bar from said shaft, and means for vibrating said needle laterally, including a second shaft located substantially at right angles to the first shaft, means for driving said second shaft from the first shaft, an eccentric member carried by said second shaft, and devices for connecting said eccentric member to said needle, whereby said needle is vibrated about the axis of the needle bar. 70
2. A sewing machine including in combination, a work support, a needle bar located and operating beneath said work support, a needle carried thereby, a driving shaft located beneath said work support, means for reciprocating said needle bar from said shaft, and means for vibrating said needle laterally including a worm gear carried by said shaft, a second worm gear coöperating with said first named gear, and having its axis located in a plane at right angles to the driving shaft, an eccentric member carried by said second gear and devices for connecting said eccentric member to said needle. 75
3. A sewing machine including in combination, a base, a work support spaced from said base, a driving shaft supported by and beneath the work support, a needle bar mounted in a bearing carried by said work support, means for reciprocating a needle bar from said driving shaft, a needle carried by said needle bar, and means for vibrating said needle laterally, including a worm gear carried by said driving shaft, a second worm gear coöperating therewith and having its axis located in a plane at right angles to the driving shaft, an eccentric member carried by said second gear, and a link for connecting said eccentric member to said needle. 80
4. A sewing machine including in combination, a work support, a needle bar mounted beneath the work support to reciprocate in a direction parallel therewith, means for reciprocating said needle bar back and forth in substantially the same path, a carrier mounted on said needle bar, a needle mounted in said carrier, and means for vibrating the carrier about the axis of the needle bar. 85
5. A sewing machine including in combination, a work support, a needle bar, means for supporting said needle bar whereby the same reciprocates in a plane parallel with the work support, means for reciprocating
- said needle bar, a carrier supported by said needle bar and projecting toward said work support, a needle mounted on said carrier, and means for vibrating said carrier about the axis of the needle bar. 90
6. A sewing machine including in combination, a work support, a needle bar, means for supporting said needle bar whereby the same reciprocates back and forth in the same path beneath the work support and in a plane parallel with the work support, means for reciprocating said needle bar, a carrier supported by said needle bar and projecting toward said work support, a needle mounted on said carrier, and means for vibrating said carrier about the axis of the needle bar. 95
7. A sewing machine including in combination, a work support, brackets carried by said work support and projecting downwardly therefrom, a needle bar mounted to reciprocate back and forth in substantially the same path in said brackets, means for reciprocating said needle bar, a carrier supported by said needle bar and projecting toward said work support, a needle mounted in said carrier, and means for vibrating said carrier about the axis of said needle bar. 100
8. A sewing machine including in combination, a work support, brackets carried by said work support and projecting downwardly therefrom, a needle bar mounted to reciprocate in said brackets, a needle carrier supported by said needle bar and movable about the axis of said needle bar, a needle mounted in said needle carrier, a bar projecting from said carrier for moving said carrier about said axis, a link connected to said bar, and means for vibrating said link. 105
9. A sewing machine including in combination, a work support, a needle bar, means for reciprocating said needle bar, a needle carrier supported by said bar, a needle mounted in said carrier, a bar fixed to said carrier and projecting therefrom, means for oscillating the carrier about the axis of the needle bar, said means including a link having a sliding connection with said bar, means for moving said link endwise for oscillating the carrier, and devices for preventing lateral movement of said link with the bar fixed to the carrier as the needle bar reciprocates. 110
10. A sewing machine including in combination, a needle bar, means for reciprocating said needle bar, a needle carrier supported by said bar, a needle mounted in said carrier, a bar connected to said carrier and extending in a direction substantially parallel with the needle bar, an arm connecting the needle bar with the bar on said carrier, means for vibrating said needle laterally including a link having a sliding connection with the bar on the carrier, means for moving said link endwise for oscillating the carrier, and 115
12. 13.

devices for preventing lateral movement of said link with the bar fixed to the carrier as the needle bar reciprocates.

11. A sewing machine including in combination, a needle bar, spaced brackets in which said needle bar reciprocates, means for reciprocating said needle bar, a carrier mounted on the end of said needle bar and projecting laterally therefrom, an arm on the needle bar between the brackets and projecting laterally therefrom, a bar connecting the carrier with said arm, said bar being substantially parallel with the needle bar, a needle mounted in said carrier, and means for vibrating the needle laterally including a link having a sliding connection with the bar between the arm and carrier.

12. A sewing machine including in combination, a work support, a needle bar mounted beneath the work support and reciprocating in substantially the same path and parallel thereto, a needle carrier supported by said needle bar, a needle mounted in said carrier, and means for oscillating the carrier about the axis of the needle bar, including a link connected to the carrier adjacent its outer end.

13. A sewing machine including in combination, a work support having a slot formed therein, a cover plate for said slot, a V-shaped bracket spanning said slot and connected to the work support, a second bracket connected to the work support, a needle bar mounted to reciprocate in said brackets, a needle carrier supported by said needle bar and projecting toward said work support, a needle mounted in said carrier, means for reciprocating the needle bar, and means for vibrating the carrier about the axis of the needle bar.

14. A sewing machine including in combination, a work support, a driving shaft beneath the work support, a needle bar mounted beneath the work support to reciprocate in a direction parallel to said support, means for reciprocating said needle bar back and forth in the same path from said driving shaft, a carrier mounted on the needle bar and projecting toward the work support, a needle mounted in said carrier, means connected with said carrier for vibrating said needle laterally, a looper movable about a fixed vertical axis, and means connected with said driving shaft for oscillating said looper about its axis.

15. A sewing machine including in combination, a work support, a driving shaft beneath the work support, a needle bar mounted beneath the work support and reciprocating in a direction parallel thereto, a carrier mounted on said needle bar, a needle mounted in said carrier, deviates operated from the driving shaft for vibrating said carrier relative to said needle bar for moving said needle laterally, a looper movable about a fixed

vertical axis, and devices connected to the driving shaft for oscillating said looper.

16. A sewing machine including in combination, a work support, a needle bar mounted beneath the work support, and reciprocating in a plane parallel therewith, a needle carried by said needle bar, means for reciprocating said needle bar, means for vibrating the needle laterally, a bender for bending the material into the path of the needle, a looper coöperating with the needle, said work support having an opening therein directly above said looper, and a thrum gathering device connected to said work support and projecting over said opening, and means for supporting said thrum gathering device whereby the same may be moved laterally to give access to the looper.

17. A sewing machine including in combination, a work support, a needle located beneath the work support, and movable in a plane parallel therewith, a bender for bending the material into the path of the needle, a lever supporting said bender, means for oscillating said lever, a feeding mechanism for feeding the material including a feed dog, a feed bar carrying the same, and an arm carried by the lever for operating the bender, said arm having a sliding connection with the feed bar, whereby the oscillating movements of the bender lever will raise and lower the feed dog and allow the feed dog to move back and forth.

18. A sewing machine including in combination, a work support, a needle located beneath the work support and moving in a direction substantially parallel thereto, means for reciprocating the needle, and means for vibrating the needle laterally, a bender for bending the material into the path of the needle, a feeding mechanism for feeding the material, a presser foot, a thrum gatherer carried by the work support for gathering the thrums on the under side of the material, and a guiding finger carried by the presser foot and extending to a point in front thereof for indicating the position of the thrum gatherer and stitching point underneath the material.

19. A sewing machine including in combination, a needle bar, means for supporting said needle bar, whereby the same reciprocates back and forth in the same path, a carrier mounted on said needle bar and projecting laterally therefrom, a needle mounted in said carrier, means for vibrating said needle carrier relative to the needle bar, and means for moving said carrier longitudinally of the needle bar during its lateral vibration.

20. A sewing machine including in combination, a needle bar, means for supporting said needle bar, whereby the same reciprocates back and forth in the same path, a carrier mounted on said needle bar and pro-

jecting laterally therefrom, a needle mounted in said carrier, means for vibrating said needle carrier relative to the needle bar, said carrier having a screw thread connection with the needle bar, whereby as it is moved laterally said carrier is moved longitudinally relative to the needle bar.

21. A sewing machine including in combination, a needle bar, means for supporting said needle bar, whereby the same is reciprocated back and forth in the same path, means for reciprocating said needle bar, said needle bar having a screw thread formed at one end thereof, a carrier having a complementary thread mounted on and engaging the screw thread of the needle bar, a needle mounted in said carrier, and means for vibrating the carrier laterally relative to the needle bar.

20 22. A sewing machine including in combination, a needle bar, means for supporting said needle bar, whereby the same reciprocates back and forth in the same path, a carrier mounted on the needle bar and projecting laterally therefrom, said carrier having a screw thread connection with the needle

bar, an arm freely mounted on the needle bar, a bar connecting said carrier and said arm, a link having a collar at its outer end freely sliding on said bar, and means for vibrating said link.

23. A sewing machine including in combination, a needle bar, means for supporting said needle bar, whereby the same reciprocates back and forth in the same path, a carrier mounted on the needle bar and projecting laterally therefrom, said carrier having a screw thread connection with the needle bar, an arm freely mounted on the needle bar, a bar connecting said carrier and said arm, a link having a collar at its outer end freely sliding on said bar, a guiding bracket for preventing said link from moving laterally, and means for moving said link longitudinally in said guiding bracket.

In testimony whereof I have signed my name to this specification in the presence of two subscribing witnesses.

GEORGE S. HILL.
